UNITED STATES PATENT OFFICE.

SYLVESTER R. BRIGGS, OF FOSTER, RHODE ISLAND.

WHISTLE.

SPECIFICATION forming part of Letters Patent No. 394,243, dated December 11, 1888.

Application filed January 17, 1888. Serial No. 261,006. (No model.)

To all whom it may concern:

Be it known that I, SYLVESTER R. BRIGGS, a citizen of the United States, residing in the town of Foster, in the county of Providence and State of Rhode Island, have invented 5 certain new and useful Improvements in Whistles; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to whistles of the class adapted to be used more especially by bicycleriders, car-drivers, and other persons in giving signals.

The invention resides, essentially, in the 20 novel construction of the mouth-piece or holder, combined with the sound-tube or air-barrel.

The object sought to be accomplished is to produce a more serviceable and practical 25 whistle of its type than has been made heretofore, and one, also, that is comparatively inexpensive, a distinguishing feature of my improved whistle being that it can be readily carried in the mouth without inconvenience, 30 owing to the novel form of the mouth-piece, which terminates in a hook-shaped portion, its presence not seriously interfering with a free use of the lips, as in talking, &c. When the whistle is not in use, it may be carried in 35 the owner's pocket or be suspended from a short chain, as common with other analogous whistles.

In the accompanying sheet of drawings, Figure 1 represents a front or perspective view of a 40 double-barreled whistle provided with my improved mouth-piece. Fig. 2 is a side view thereof. Fig. 3 is a vertical sectional view taken through the center of the upper portion of one of the barrels and the connected 45 mouth-piece, the line of section taken being that of x x , Fig. 1. Fig. 4 is a front view of the whistle as provided with a single barrel, and Fig. 5 is a side view looking into the mouth-piece from the rear side.

50 The following is a more detailed description of my invention, including the manner of its construction and general operation.

A designates the whistle complete, combining my improvements, the parts comprising the same being preferably made from sheet 55 metal and soldered. Obviously, the whistles may be plated and made very ornamental, if desired.

a indicates the sound tube or barrel closed at the bottom end and having its upper end 60 open and cut or beveled, so as to form quite an angle with the axis of the tube, as shown at c.

b designates the hollow mouth-piece or holder secured at an angle to the longest side of said tube, the under side of the holder coinciding with and forming a prolongation of the beveled end of the tube, as clearly shown in Fig. 3. The outer end, i, of the holder is made, preferably, somewhat narrower than the opposite end, h, contiguous to the tube. At 70 its junction with the lateral sides of the tube the holder extends nearly to the center. The vertical sides e of the holder are closed. It will be noticed that the outlet h has the appearance of being contracted. Practically, 75 however, the areas of the two ends are about the same. The upper side of the holder at its free end is slightly rounded, as at r, and the corresponding portion of the under side extends beyond the edge r somewhat, and is also 80 rounded and bent downwardly to form a hook, d, thereby when in use adapting it to rest upon and be retained by the under lip of the person carrying it. For convenience in attaching a chain or cord a wire loop, m, is secured to the bottom end of the tube.

When two tubes are used, it is better to have them of unequal lengths, as shown, as the quality and volume of emitted sound are greatly improved thereby.

When in use, the hook portion d of my improved mouth-piece rests well in and upon the under lip, the center of gravity of the whistle causing the lower portion of the barrel to lie against the chin and adapting the 95 instrument to be held in position with a very little effort.

I claim as new and desire to secure by United States Letters Patent—

1. As an improved article of manufacture, 100 the whistle hereinbefore described, having a tubular or barrel portion closed at one end and beveled at the other, and, further, having a hollow mouth-piece or holder secured at an

angle to the barrel and coinciding with said beveled end, and having a hook-shaped projection formed on the under side of the mouth-piece at its free end, substantially as specified.

5 2. The improved whistle hereinbefore described, consisting of a barrel portion closed at the bottom end only, and having a beveled upper end to which is secured a mouth-piece having a contracted opening, and a bent or 10 hook-shaped portion adapted in use to lie upon and be supported by the under lip.

3. The combination of a sound-tube closed at the bottom and cut off at an angle at the top end, and a hollow mouth-piece secured

thereto having closed sides, a contracted outlet having its lower side coinciding with said angularly-cut portion, and a well-rounded lip portion bent to a hook shape, as *d*, formed at the outer or free end of the mouth-piece, substantially as shown and hereinbefore de- 15 scribed, and for the purpose specified.

In testimony whereof I have affixed my signature in presence of two witnesses.

SYLVESTER R. BRIGGS.

Witnesses:

CHARLES HANNIGAN,
GEO. H. RENNINGTON.
